UNITED STATES PATENT OFFICE

KYLE E. STANT, OF CONNERSVILLE, INDIANA, ASSIGNOR TO THE STANT MACHINE COMPANY, OF CONNERSVILLE, INDIANA, A CORPORATION OF INDIANA

RADIATOR CAP

Application filed October 25, 1928. Serial No. 315,031.

My invention relates to closures for receptacles and particularly to radiator caps for that purpose.

It is the object of my invention to provide a radiator cap that carries a non-rotatable, non-yielding, locking device, and a rotatable, flexible, sealing device, or a non-rotatable, flexible sealing device.

It is a further object to provide in such a combination a sealing device in which there is a combination of a relatively compressible sealing medium expansible in the presence of liquids and heat, and a yielding backing member that provides the necessary strength for maintaining the sealing member in position.

It is a still further object of my invention to provide a positive non-yielding cam lock so that the rigidity between the locking parts may be secured, while the maintenance of the locking parts in engagement with one another may be yieldingly accomplished to prevent the escape of liquid, and insure against rattling by providing means independent of the locking parts of both yielding and sealing nature.

Referring to the drawings,

Figure 1 is a vertical section through the filler spout and radiator cap in locked position.

Figure 2 is a bottom plan view thereof.

Figure 3 is a detailed plan view of the locking cups carried on the radiator cap.

Figure 4 is a side elevation thereof.

Figure 5 is a detailed section through the method of attachment of the locking cup sealing member and yielding backing therefor, with the radiator cap.

Figure 6 is a bottom plan view of the filler spout without the radiator cap.

Figure 7 is a section through the filler spout without the filler cap.

Figure 8 is a perspective of the inside of the radiator cap without the yielding, sealing and locking members.

Referring to the drawings in detail, 1 is a filler spout of a radiator or the spout of any receptacle. It is provided with an inwardly extending, upward, marginal shoulder 2 which turns inwardly and downwardly as at 3.

This spout has depending from these

spaced, inwardly depending shoulders 3 stop lugs 4. The lower edges of these depending members 3 are provided with cam surfaces 5. Engaging with these cam surfaces 5 and the stop lugs 4 are non-yielding, laterally extending, locking fingers 6 extending outwardly from the lower margin of a locking cup 7, which is provided with a square aperture 8 in the center for mounting upon the square shoulder 9 of the radiator cap 10. This shoulder is mounted upon a depending finger 11 of the radiator cap.

The cup is retained in position either by having the end 12 of the depending finger 11 of the radiator cap 10 turned over and swaged in the nature of a rivet or a screw 13 may be employed which is threaded as at 14 in the depending member 11 so that the degree of clamping the cup against the seating washer 15 and its yielding backing of brass 16 may be adjusted.

The washer 15 and the brass disc 16 are rotatably mounted upon an annular shoulder 17 on the lower end of the depending member 11, so that they can freely rotate thereon if the adjustment of the clamping screw 13 permits. A lock washer 18 is provided in association with this screw for locking it in position.

The inner portion of the radiator cap 10 is provided with stop lugs 19 for engaging with the upper side of the yielding brass plate 16 if desired.

The engagement of lugs 19 with the top of plate 16 prevents said plate from becoming distorted beyond a predetermined plane or shape. Sufficient space must be provided however between the plate and the lugs so that vertical movement of the plate will not be arrested to a degree that would cause interference with complete rotation of the cap into locking engagement with the spout.

While I prefer to make the sealing member of fiber which expands in the presence of hot water such as is found in radiators, yet any other form of sealing member may be employed. Likewise the brass disc 16 may be of any thin, yielding material. It is not necessary for the yielding member and the

sealing member to both rotate, but it is found desirable.

I have found it very advantageous however to have a non-yielding, locking mechanism 5 consisting of the locking fingers 6 and the filler spout cam lock with a separate yielding and sealing means for maintaining the parts, one in engagement with the other, because the use of heavy parts for locking permits of a 10 very effective lock of long life, in combination with a more effective seal which can be made of thin, yielding and expansible material, thereby avoiding the disadvantage of some 15 types of construction in which the locking means is also yielding which defeats the efficiency and durability of a positive lock.

It will be understood that I desire to comprehend within my invention all the modifications necessary to adapt it to varying 20 conditions and uses.

Having thus fully described my invention, what I claim as new and desire to protect by Letters Patent is:

1. In a closure for receptacles, a filler spout 25 having locking members, a radiator cap having a depending, non-rotatable, cooperating locking member and locking fingers thereon, a sealing means for sealing the cap to the filler spout, and yielding means backing the 30 said sealing means in engagement with the filler spout and the radiator cap, said yielding means being rotatably mounted on the radiator cap, and portions of said yielding means being spaced from the cap during rotation of said cap up to its locked position.

2. In a closure for receptacles, a filler spout having locking members, a radiator cap having a depending, non-rotatable, cooperating locking member, a sealing means for 40 sealing the cap to the filler spout, yielding means for holding the said sealing means in engagement with the filler spout and the radiator cap, said yielding means being rotatably mounted on the radiator cap, and 45 portions of said yielding means being spaced from the cap during rotation of said cap up to its locked position.

3. In a closure for receptacles, a filler spout having locking members, a radiator 50 cap having a depending, non-rotatable, cooperating locking member, a sealing means mounted on said radiator cap adapted for sealing the filler spout, yielding means for holding the said sealing means in engagement with the filler spout and the radiator cap, said last mentioned sealing and yielding means being rotatably mounted on the radiator cap, and portions of said yielding means being spaced from the cap during 55 rotation of said cap up to its locked position, and stops on the filler spout for cooperating with the non-rotating locking means on the radiator cap for positioning the radiator cap when in locked position.

4. In a mechanism for a closure of a recep-

tacle, a filler spout, a non-yielding locking means on said filler spout, a cap, a non-yielding locking means on said cap, and yielding means thereon for maintaining the non-yielding locking means in engagement and 70 closing the opening in the filler spout, said yielding means being rotatable on the radiator cap and the locking means carried by the radiator cap non-rotatable thereon and portions of said yielding means being spaced 75 from the cap when said yielding means is in engagement with said spout during rotation of said cap up to its locked position.

5. In a mechanism for the closure of a receptacle, a non-yielding locking means on a 80 filler spout, a non-yielding locking means on a radiator cap, a radiator cap, yielding means thereon for maintaining the non-yielding locking means in engagement with one another, said yielding means being rotatable 85 on the radiator cap and the locking means carried by the radiator cap non-rotatable thereon, and means for adjusting the degree of rotation of the yielding means on the radiator cap.

6. In a mechanism for the closure of a receptacle, a non-yielding locking means on a 90 filler spout, a non-yielding locking means on a radiator cap, a radiator cap, yielding means thereon for maintaining the non-yielding 95 locking means in engagement with one another, said yielding means being rotatable on the radiator cap and the locking means carried by the radiator cap non-rotatable thereon, and means for adjusting the degree 100 of rotation of the yielding means on the radiator cap and of detachably retaining the radiator cap locking means thereon.

7. In combination in a radiator cap of a 105 cap body, a depending central member having a yielding member shoulder with an annular throat, and a narrower square throat adjacent thereto with a shoulder of smaller diameter than the first shoulder for receiving a locking member, a yielding means on the first shoulder rotatably of the cap, a non-yielding locking member mounted on the second shoulder arranged to prevent the removal of the yielding means from its shoulder and the clamp throat, and means for retaining the locking means on the depending member of the radiator cap, said last mentioned means being adjustable to adjust the clamping of the yielding means between the locking means and the first shoulder on the 110 depending member of the radiator cap.

8. In combination in a radiator cap of a 115 cap body, a depending central member having a yielding member shoulder with an annular throat, and a narrower square throat adjacent 120 thereto with a shoulder of smaller diameter than the first shoulder for receiving a locking member, a yielding means on the first shoulder rotatably of the cap, a non-yielding locking member mounted on the second shoulder 125 130

arranged to prevent the removal of the yielding means from its shoulder and the clamp throat, means for retaining the locking means on the depending member of the radiator cap, 5 said last mentioned means being adjustable to adjust the clamping of the yielding means between the locking means and the first shoulder on the depending member of the radiator cap, and an expansible washer mounted between the yielding means and the locking means, adapted to be yieldingly reinforced by the yielding means.

9. In combination, a filler spout having inwardly and downwardly disposed spaced cams, positioning shoulders associated therewith, a radiator cap, a depending member on the interior thereof, a non-yielding, rigid, locking member extending laterally therefrom, adapted to engage with said cams and 15 said stops, shoulders on said cap to prevent the rotation of the locking fingers thereon, yielding means interposed between the top of the filler spout and the radiator cap for closing the opening between the radiator cap 20 and the filler spout, and an intermediate washer between said means and the filler spout adapted to expand in the presence of heat and moisture, and portions of said yielding means being spaced from the cap during 25 rotation of said cap up to its locked position.

10. In combination, a filler spout having inwardly and downwardly disposed spaced cams, positioning shoulders associated therewith, a radiator cap, a depending member on the interior thereof, a non-yielding, locking member having fingers extending laterally therefrom, adapted to engage with said cams and said stops, cams on said cap to prevent the rotation of the locking fingers thereon, 35 yielding means interposed between the top of the filler spout and the radiator cap for closing the opening between the radiator cap and the filler spout, and an intermediate washer between said means and the filler spout 40 adapted to expand in the presence of heat and moisture, said yielding means and washer being so arranged as to freely rotate upon the radiator cap, and portions of said yielding means being spaced from the cap when 45 said washer is in engagement with said spout during rotation of said cap up to its locked position.

11. In a closure for receptacles, a filler spout having locking members, a cap having 55 a depending rigid cooperating locking member thereon and a resilient closing and retaining plate having resilient portions spaced from the cap when said plate is in engagement with the filler spout during rotation of said 60 cap up to its locked position.

12. In a closure for receptacles, a filler spout having locking members, a cap having a depending cooperating rigid locking member and a yielding closing and retaining 65 means having yielding portions spaced from

the cap when said yielding means is in engagement with the filler spout during rotation of said cap up to its locked position.

In testimony whereof, I affix my signature.
